2 SHEETS—SHEET 2.

UNITED STATES PATENT OFFICE.

JOHN TANDY, OF BUTTE, MONTANA.

DAMPER.

1,410,138.

Specification of Letters Patent. Patented Mar. 21, 1922.

Application filed September 1, 1921. Serial No. 497,524.

To all whom it may concern:

Be it known that I, JOHN TANDY, a citizen of the United States, and a resident of Butte, in the county of Silver Bow and State of 5 Montana, have invented certain new and useful Improvements in Dampers, of which the following is a specification.

My invention relates to fireplace dampers, and is intended as an improvement upon the 10 damper for which patent issued to me December 7, 1920, No. 1,361,782, and has for an object to provide a device of the character specified adapted for use in fireplaces to control the draft wherein a housing or frame 15 is provided of a size to register with the opening of the flue, and shaped to conform with the proper arrangement of the junction of the fireplace and the flue, and having a damper capable of being operated from outside the flue for regulating the draft through the flue.

Another object is to provide a damper of this character with means for indicating the opening and closing of the damper.

25 In the drawings,

Figure 1 is a front view of the fireplace showing the operating handle and indicator,

Figure 2 is a horizontal section above the housing,

30 Figure 3 is an enlarged horizontal section of rear wall of housing,

Figure 4 is a vertical section through the fireplace and housing,

Figure 5 is an enlarged sectional view 35 showing the operating mechanism,

Figure 6 is a sectional elevation showing one of the shaft bearings,

Figure 7 is a transverse section taken on line 7-7 of Figure 5,

40 Figure 8 is a similar section taken on line 8-8 of Figure 5,

Figure 9 is a similar section taken on line 9-9 of Figure 5,

Figure 10 is a longitudinal section through 45 the operating shaft showing the indicator and operating mechanism.

In the present embodiment as in my former patent, the invention is shown in connection with a fireplace having the opening 50 or combustion chamber 1 and flue 2 with which the combustion chamber communicates, the fireplace and flue being constructed of brick. The rear wall 3 of the fireplace is inclined forwardly and there is provided 55 a soot shelf 4 at the top of this wall 3, the

top being inclined forwardly in front of the flue 2.

The front of the top of wall 3 is a little forward with respect to the front wall of the flue, thus providing a throat at this point 60 between the flue and the fireplace in which is placed the housing.

The housing consists of an inclined front wall 5 having a horizontal plate or shelf 6 projecting from its front face serving as a 65 medium for supporting brickwork. The housing further includes a vertical rear wall 7 having a central or otherwise vertical corrugation 8 which is provided with a series of openings 9 to support and provide room 70 for the shaft which operates the damper as will be hereinafter more fully set forth. In addition to the walls 5 and 7 the housing includes side walls 10 which incline downwardly, and a bottom wall 11, which is a cover 75 for the soot shelf.

The housing is in practice preferably a cast iron structure having its inner face flush with the inner face of the flue and throat, supported by the masonry below the 80 housing and itself supporting the masonry above.

As shown in Figure 5, the front wall 5 and a portion of side walls 10 extend below the level of the soot shelf 4, and a damper plate 12 is hinged at its lower end to the soot plate 11 as indicated by 4^a in such manner that its lower edge when it is in closed position, rests upon the soot plate 11 at its forward edge, the upper edge of the 85 damper 12 engaging the inclined front wall 5, and its ends engaging the side walls 10.

In order to control the damper a screw threaded shaft 13 is mounted in the masonry. This is accomplished by providing the bearing 14 and its purpose is to keep the operating rod or shaft 13 in a permanent position after brickwork is built around it, the flanges 15 located in the masonry joints 16. The little flange 17 on the handle 18 in front 90 performs the same duty only in the reverse way. This bearing also prevents any possibility of gases passing through and does not turn. Without the use of this bearing the shaft would gradually wear the brickwork and pull out more or less.

As shown the shaft 13 is slotted as indicated by 13^a in Figure 8, and in this slot is placed an indicator rod 19 which passes 95 through the center of the hollow rod 40 of 110

the screw shaft, this rod being extended from the slot in the screw shaft and passing through bearing 14 and extending beyond the front wall where it has attached to it, 5 the handle 18 before referred to. This handle which has a central bore permits the end of the indicator rod to project outwardly in front of the fireplace. The inner portion of the rod 19 is bent upwardly as at 10 20, through the slot, then forwardly as at 21, and has a downwardly projecting lug 22 at the extreme end which extends down upon the nut beyond the annular flange or rim 13^b at the forward end of the nut.

15 To the rear end of the screw or worm shaft 13 is secured a small rod 23 which extends rearwardly and through the opening 9 in the central corrugation 8 of the rear wall 7 of the housing, thus supporting the 20 screw shaft in proper horizontal position. This rod 23 is secured in the end of screw shaft 13 by a cotter pin 24 which will also serve to prevent the nut running off the screw shaft 13. The rod 23 supporting the 25 screw shaft 13 leaves it free to rotate and at the rear provides more room for rod to slide without piercing brickwork.

30 A nut 25 is mounted on the threaded portion of the shaft 13 and a rod 26 is hinged at one end to the nut by the ears 26^a which are made integral with the nut. The rod 26 extends through a sheath 27 on the damper plate, which sheath is here shown as generally wedge or triangular shape, so that when 35 the damper is open, the sheath will lie on the soot shelf 4 and bottom wall 11 of the housing.

40 The end of rod 26 which passes through the sheath 27 normally extends below the soot shelf, as shown in Figures 4 and 5, and the upper edge of the damper plate is slotted vertically as at 28 to permit passage of screw or worm shaft 13, as shown in Figure 5.

45 The length of the rod 26 is such that it cannot become disengaged from the damper at any time, whatever the position of the sheath.

50 The front wall 5 is slotted as at 29 for the screw shaft 13, and the lower edge of this wall rests upon the angle plate 30 (see Figure 1), which supports the arch of the fireplace or superimposed masonry.

55 The indicator or signal 19 is an important feature of this invention, its purpose being to warn the person operating, whether the damper gate is closing or opening and to make practically impossible the closing of the damper without knowing it, as the indicator rod will press into the hand when the 60 damper is closing as it will protrude about one inch. As the operation of the damper cannot be seen the indicator becomes an indispensable feature. When the screw shaft 13 is being turned, the nut 25 moves back and forth and pulls or pushes the in-

dicator; the rim or flange 13^b on the nut anchors the end 22 of the indicator rod so that it will pull when the damper is opening and push when the damper is closing, but anchoring indicator over rim on nut is optional in practice, when not anchored only a forward movement will occur, the person operating pushes indicator back. Upon the front down hanging portion of the soot shelf 4 is provided an eye 31, the purpose of 75 which is to hang a kettle (not shown), or by means of a hook, if necessary.

The purpose in slotting the screw shaft is to make possible successful working of indicator, and it is optional whether it (the slot) 80 passes completely through the screw shaft or just below the indicator rod 19. This rod passes through the handle 18 and along the center of the three-eighth inch pipe or core 40, which in turn engages with the slot in 85 the main screw shaft 13, and is then sprung over the rim or flange 13^b of the nut.

It should be noted that the operating shaft will always fall into a joint and its handle fit the face of the brickwork. It can be 90 raised or lowered vertically and moved horizontally in and out without moving the housing.

I claim:

1. In a fireplace, the combination with 95 the fireplace, the flue and the throat connecting the fireplace and flue, of a housing shaped to fit the throat and provided with a soot shelf, a damper, and means operable outside the flue for moving said damper 100 into vertical position transversely of the throat or into inclined position to leave the throat open, said means comprising a rotatable screw shaft journaled in the housing, the damper having sheath or socket inclined 105 with respect to the plane of the damper, a slidable rod engaging said sheath, a nut threaded onto said rotatable screw shaft and hinged to the upper end of said slidable rod, and an indicator rod carried by said 110 shaft, one end projecting through the operating end of the screw shaft, and the other end adapted to be engaged by the travelling nut by pushing or pulling, whereby the indicator rod will be moved in or out to indicate the movement of the damper.

2. In a fireplace, the combination with the fireplace, the flue and the throat connecting the fireplace and the flue, of a housing shaped to fit, and to form the throat, a 120 damper hinged within said housing, and means for operating said damper from the outside of the flue, said means comprising a worm shaft journaled in said housing, and having an operating handle connected therewith outside the fireplace, said shaft having a slotted portion, an indicator rod slidably mounted in said slotted portion, one end projecting through said operating handle and the other end projecting from said slot.

ted portion of the screw shaft and engageable by a nut on the screw shaft, a nut provided with means for engaging said end of the indicator rod, and a slidable rod engaging said damper, and pivotally connected at one end to said nut.

5. Damper operating means as set forth in claim 3, and further characterized by means adjacent the end of the screw shaft to prevent the nut from travelling beyond the 10 threads thereof.

4. In a fireplace, the combination with the fireplace, the flue and the throat connecting the fireplace and the flue, of a housing 15 shaped to fit and to form the throat, said housing including an inclined front wall, end walls, a bottom plate and a rear wall, the rear wall having a central inwardly extending vertical corrugation provided with 20 a plurality of openings, and said inclined front wall having a vertical slot there-through, and a threaded damper-operating shaft journaled in said slot, and an opening 25 in the vertical corrugation of the rear wall of the housing.

5. In a fireplace, the combination with the fireplace, the flue and the throat connecting the fireplace and the flue, of a housing shaped to fit the throat and provided with a 30 soot shelf, a damper hinged to the soot shelf,

and means operable outside of the flue for moving said damper into various angular positions transversely of the throat, said means comprising a worm shaft carrying a longitudinally movable nut, and journaled 35 in said housing, a rod hingedly connected at one end to said nut and slidably engaging said damper, and an indicator rod carried by said screw shaft and adapted to be engaged by said nut in its longitudinal 40 movements, to push and pull the said indicator rod whereby movement of the damper will be indicated outside the flue.

6. In a fire place, the combination with the fire place including the flue and the 45 throat connecting the same, a damper hinged within the throat, of means operable outside the flue for moving said damper into various angular positions transversely of the throat, said means comprising a threaded horizontal 50 shaft, a nut longitudinally movable thereon, a rod flexibly connected at one end to said nut and movably engaging the damper, and an indicator rod movably mounted with respect to said threaded shaft and adapted to 55 be engaged by said nut in its longitudinal movements, whereby movement of the hinged damper will be indicated outside the flue.

JOHN TANDY.
